Specification for Design.

Patented May 21, 1918.

Application filed March 13, 1918. Serial No. 222,247. Term of patent 14 years.

To all whom it may concern:

Be it known that I, RALPH A. BELMONT, residing at New York, in the county and State of New York, have invented a new, original, and ornamental Design for a Casing for a Feed-Through Switch, of which the following is a specification, reference being had to the accompanying drawing, forming part thereof, in which—

Figure 1 is a perspective of a casing embodying my design;

Fig. 2 is a front elevation of the same;

Fig. 3 is an end elevation thereof; and

Fig. 4 is a top plan thereof.

What I claim is:

The ornamental design for a casing for a feed through switch, as shown.

RALPH A. BELMONT.
